OF ONE-HALF TO LIONEL WILLIAM JOHN DIGBY, OF HAYCOCK, WANSFORD, ENGLAND.

ALLOY.

No. 867,194.

Specification of Letters Patent.

Patented Sept. 24, 1907.

Application filed July 20, 1906. Serial No. 327,085.

To all whom it may concern:

Be it known that FREDERICK WILLIAM FLETCHER, a subject of the King of Great Britain, residing at Helpston, Market Deeping, Lincolnshire, England, has invented certain new and useful Improvements in Alloys, of which the following is a specification.

The object of this invention is to manufacture a metallic alloy.

For the purpose of this invention, I take aluminium, gun metal (preferably soft formed from 90 parts of copper and 10 parts of tin) and white metal formed from a mixture of 6 parts tin with one part copper admixed with a mixture of 6 parts tin and one part of antimony in or about the following proportions:

15   Aluminium = 30 lbs.
                      Gun metal = 1 lb.
                      White metal = $\frac{1}{4}$ lb.

and melt them together, stirring the mass after becoming fluid until thoroughly amalgamated.

20   I cast the metal into molds in strip form to form ingots for after use in making of articles in any well known way.

What I claim and desire to secure by Letters Patent is:—

1. A metallic alloy for shoes of beasts of burden, consisting of aluminium, gun metal (formed from a mixture of 90 parts of copper and 10 parts of tin), and white metal (formed from a mixture of 6 parts tin with 1 part copper admixed with a mixture of 6 parts tin and 1 part antimony) melted and alloyed together in or about the following proportions, aluminium 30 lbs., gun metal 1 lb., white metal $\frac{1}{4}$ lb., substantially as set forth.

2. A metallic alloy consisting of aluminium, gun metal and white metal.

3. A metallic alloy consisting of thirty pounds of aluminium, one pound of gun metal, one-quarter pound of white metal.

In testimony whereof I have hereunto set my hand in presence of two subscribing witnesses.

FREDERICK WILLIAM FLETCHER.
